CLAMSHELL BUCKET

Edward L. Harrington, Pittsburgh, Pa., assignor
to Blaw-Knox Company, Pittsburgh, Pa., a cor-
poration of New Jersey

Application November 13, 1941, Serial No. 418,937

5 Claims. (Cl. 37—186)

This invention relates to a clam shell bucket, and, in particular, to a "clean-up" bucket.

A cleanup bucket is one used to remove coal, ore or other material from a ship or barge after the greater part of the cargo has been removed by another type of grab, or other means. It is not required to dig downward into a deep pile, but to scrape together material spread out over a large area of the ship bottom or barge deck. Such buckets open out to secure wide spread, and require only sufficient "closing power" to enable them to scrape together the material between their widely spread jaws or lips, and then to close the lips to prevent spilling.

Such buckets are operated by means of cables reeved over sheaves within the bucket and pulled in or paid out by means of hoists in the crane or bridge by which the buckets are operated. The forces necessary to close the bucket must be supplied by the cables. The amount of the force required to close a cleanup bucket depends upon the spread and the weight of the bucket to a greater extent than upon the amount of material it gathers up during the closing operation. It is desirable to keep the amount of cable that must be wound up on the hoisting drum to close the bucket on a level deck, as small as practicable in order to expedite the closing and opening operations; but on the other hand, it is necessary to have enough cable pulled to exert the necessary closing force to insure closure with a full load before the bucket is lifted.

Cleanup buckets hitherto known have been characterized by complexity of the reeving of the closing line within the bucket, by the necessity of a number of moving parts to preserve reasonable straightness of lines from sheave to sheave, and in the case of large buckets by the necessity of pulling a greater length of line in the closing operation than is required to gather up a full load of material. The chief objects of the present invention are to avoid this complexity by simplifying the reeving, and to lessen the length of line it is necessary to pull, to close the bucket under normal working conditions of operation, thereby making it possible to handle more loads of material per hour with a given crane and hoist speed. The simplification of reeving also makes possible some saving of weight in the bucket structure, and therefore a greater proportion of "pay" load to total weight of loaded bucket of a given maximum spread.

I have invented a novel form of clean-up bucket which largely overcomes the aforementioned difficulties of buckets of this type as known pre-

viously. In a preferred embodiment, the invention comprises a pair of hinge frames pivoted to a head and depending therefrom, having scoops secured to the lower portions thereof. A sheave block between the hinge frames has toggle links pivoted thereto and to the frames effective to open the bucket when suspended by a sheave in said block. I provide a pair of closing sheaves generally in the lower portion of each frame, guide sheaves journaled in said head and a cross-over sheave journaled in one of the hinge frames. A closing line has a bight around the cross-over sheave and leads extending around the closing sheaves in the frame in which the cross-over sheave is journaled, thence around the closing sheaves of the other frame and thence around the guide sheaves and upwardly through the head.

For a complete understanding of the invention and the novel features and advantages thereof, the following detailed description and explanation are given, referring to the accompanying drawings illustrating the aforementioned preferred embodiment. In the drawings:

Figure 1 is a side elevation showing a clean-up bucket according to my invention in closed position;

Figure 2 is a similar view showing the bucket in wide open position;

Figure 3 is a partial end elevation; and

Figure 4 is a partial transverse section taken along the plane of line IV—IV of Figure 1.

Referring now in detail to the drawings, a bucket according to my invention is indicated generally at 10 and comprises a pair of hinge frames 11 and 12 having scoops 13 and 14 secured to the lower ends thereof respectively, the frames being pivoted on a head 15. The hinge frames 11 and 12 are substantially identical and are of fabricated metal plate construction, each comprising outer webs 16 and 17, and inner webs 18 and 19 formed by welding plates of suitable size and shape to connecting gussets 20, 21, angles or other structural members 22 and internal braces 23 (see Figures 3 and 4). The inner and outer webs are brought together adjacent their upper ends providing built-up bearing portions 16a and 17a. The scoops 13 and 14 are likewise of fabricated metal plate construction and are secured to the lower ends of the hinge frames by any suitable means such as rivets (not shown).

The head 15 is simply a box-like structure likewise of fabricated, metal-plate construction including cross channels 27 and connecting

channels 28. Hinge shafts 30 extend transversely through the head 15 and the bearing portions 16a and 17a of the frames 11 and 12 which are provided with hubs 31 adapted to receive the protruding ends of the shafts. Meshing gear segments 32 are secured to the frames 11 and 12 at the inner portion of their upper ends, to insure proper coordination of said frames with head 15.

A sheave block 33 is disposed between the frames 11 and 12. A sheave wheel is journaled in the block 33 and is enclosed within a housing 34. Toggle links 35 are pivoted to the lower end of the sheave block 33 by shafts 36. The links 35 also have meshing gear segments 37 thereon to insure proper coordination with each other and the hinge frames. At their upper ends, the links are provided with hubs 38 through which extend transverse shafts 39 supported in suitable bearings secured to the inner webs 18 and 19 of the hinge frames. An opening cable 40 extends around the sheave journaled in the block 33, entering and leaving by suitable holes 41 in the housing 34 and extending upwardly through the head 15 to the trolley of an over-head crane.

Each of the hinge frames 11 and 12 has a pair of closing sheaves 42 and 43 journaled therein. These sheaves are journaled on pins 44 carried on the inner webs 18 and 19 and bearing brackets 44a adjacent the scoops 13 and 14. Each sheave has a cable guard 45 extending partly around it with a cable opening 46 therein.

The frame 12 has two spaced channels 47 extending thereacross supporting a shaft 48 on which is journaled a cross-over sheave 49. As clearly shown in the drawings, this sheave lies in a plane generally parallel to the axes of the shaft 30 and has a cable guard 50 extending therearound with guides 51 for leading cable to and from the score of the sheave.

Guide sheaves 52 and 53 are journaled on the head 15, the latter being provided with spaced depending plates 54 and 55 forming bearing brackets for the sheaves respectively.

A closing cable 56 has a bight extending around the sheave 49 and leads extending therefrom around the sheaves 42 and 43 journaled in the hinge frame 12. The leads extend thence around the corresponding sheaves of the hinge frame 11, upwardly around the sheaves 52 and 53, and up through the head 15 to the crane trolley. Anti-friction rollers 57 and 58 disposed at right angles are journaled in the head 15 to prevent chafing of the leads of the opening cable 40 and the closing cable 56.

Having completely described the structure of a preferred embodiment of the invention, it now remains to explain the operation thereof. Figure 2 illustrates the parts in the positions they occupy at the start of a loading and lifting operation, the exposed edges of the scoops resting on a layer of material to be handled, lying, for example, in the bottom of a ship's hold. With the parts in this position, the opening cable 40 is slightly slackened and the closing operation is effected by taking in one or both the leads of the closing cable 56. It will be apparent from a consideration of Figure 2 that the taking in of the cable 56 will exert a strong force tending to close the bucket scoops, through a substantial lever arm, because of the location of the sheaves 42 and 43 near the lower ends of the frames 11 and 12. As the scoops 13 and 14 are drawn together, the sheave block 33 is forced downwardly

5 by the links 35 and the opening cable 40 must be slackened sufficiently, as above stated, to permit this; otherwise, the bucket will be bodily lifted before it has fully closed and may thus pick up only a part load or no load at all.

With sufficient slack in the opening cable 40, the exposed edges of the scoops 13 and 14 scrape across the surface of the floor or deck on which lies the material to be handled. When the scoops are finally brought together as shown in Figure 1, they will have gathered a load of material and the bucket is then ready to be hoisted and dumped. The bucket is hoisted by taking in the opening and closing cables simultaneously. This distributes the load among the several cables and insures that the parts of the bucket remain in the position shown in Figure 1 until it is desired to dump the load. When the bucket has been moved to the desired point as by operation of the crane and trolley, it may be dumped by paying out the closing cable while securing the opening cable. Considering Figure 1 it will be apparent that if the entire weight of the bucket and load are carried on the cable 40, as will be the case when the closing cable is paid out, this whole weight will be effective to cause all parts of the bucket to descend relative to the sheave block 33 which is held fixed in space. As the remaining portions of the bucket descend, the bucket is opened by the swinging of the links 35. Downward movement of the bucket as a whole relative to the block 33 is limited by the engagement of the latter with a suitable bumper 59 positioned centrally of the head 15. For cooperation with the bumper 59, the block 33 is provided with a pad 60. When the bucket has been fully opened, as above described, and the load dumped, it may be returned to the loading point and lowered bodily for a further filling and lifting operation.

It will be apparent that, by virtue of the location and positioning of the closing sheaves and the reeving of the closing cable, ample force may be exerted on the hinge frames to close the bucket scoops under practically any operation conditions, without excessive stress in the closing cable. This is because the closing force is applied close to the scoops, through a substantial lever arm from the pivotal axes of the hinge frames. In addition, the construction of my clean-up bucket is relatively simple and involves but a small number of moving parts so that the initial cost and upkeep thereof are correspondingly lower than those of buckets of similar type known heretofore.

60 The arrangement of the closing sheaves and the reeving of the closing cable, furthermore, permit the bucket to be fully closed from its extreme open position by taking in a length of the closing cable which is smaller than that which must be taken in to close buckets of previous constructions. Since the operating time of a bucket is generally proportional to the amount of closing line which has to be taken in to effect a closing thereof, my invention represents an improvement over prior practice in this respect. The relationship between the cross-over sheave and the closing sheaves journaled in the same hinge frame is fixed so that no special provisions are necessary to hold the sheaves in cooperative relation. The arrangement of the sheaves and the reeving of the cables is such as to avoid interference with the other moving parts such as the sheave block 33 and toggle links 35. The entire construction, furthermore, is readily accessible in all parts for

inspection and repair. The provision of the guide sheaves 52 and 53 positions the outgoing leads of the closing cable relative to the leads of the opening cable so that they may readily be operated by a conventional crane trolley.

Although I have illustrated and described but a preferred embodiment of the invention, it will be recognized that changes in the construction and arrangement of the parts may be made without departing from the spirit of the invention or the scope of the appended claims.

I claim:

1. In a clamshell bucket of the wide-opening type comprising a pair of frames hinged to an upper head structure, cooperating opposed scoops at the lower extremities of said frames and cable-operated mechanism for spreading the scoops apart and for drawing them together, said mechanism including two sheaves pivoted to said head structure in different planes, parallel with the plane in which said frames swing during opening of the scoops, two sheaves pivoted to one of the aforesaid frames, in the same planes as the two aforesaid sheaves, but close to the scoop, two sheaves pivoted to the other of said frames, in the same planes as the aforementioned sheaves, and a seventh sheave pivoted in the upper part of said other frame in a plane at right angles to the plane in which said frames swing, and a cable reeved partially around all seven of the sheaves, both ends thereof passing upward through the bucket head.

2. A clamshell bucket comprising a head, a pair of hinge frames pivoted on said head, cooperating scoops secured to the lower ends of said frames, respectively, a pair of closing sheaves journaled in the lower portion of each hinge frame, a cross-over sheave journaled in one hinge frame above the closing sheaves thereof and a closing cable having a bight around said cross-over sheave and

leads extending therefrom around aligned pairs of closing sheaves in the two hinge frames.

3. A clamshell bucket comprising a head, a pair of hinge frames pivoted on said head and depending therefrom, cooperating scoops secured to the lower ends of said frames, respectively, a pair of closing sheaves journaled in the lower portion of each hinge frame, guide sheaves journaled in said head, a cross-over sheave journaled in one hinge frame above the closing sheaves thereof and a closing cable having a bight around said cross-over sheave and leads extending therefrom around aligned pairs of closing sheaves in the two hinge frames and upwardly around said guide sheaves and through said head.

4. A clamshell bucket as defined by claim 2 characterized by said closing sheaves being journaled on axles substantially parallel to the pivotal axes of the hinge frames and said cross-over sheave lying in a plane substantially parallel to said axes.

5. A clamshell bucket comprising a head, a pair of frames pivoted to said head, opposed cooperating scoops secured to the lower ends of said frames, means coordinating the movement of the frames with respect to the head to insure alignment of the scoops, one in opposition to the other, a pair of sheaves pivoted in the lower portion of each frame above said scoops, the corresponding sheaves in the two frames being in alignment, a cross-over sheave pivoted in one of said frames nearer to the head than the aforementioned sheaves, two sheaves pivotally supported from the head in alignment with the pair of sheaves in the other frame, a closing cable reeved part way around all seven sheaves mentioned, both ends whereof extend upward through the head, and means for spreading said scoops when tension in said closing cable is relaxed.

EDWARD L. HARRINGTON.
